UNITED STATES PATENT OFFICE.

JOHN ALEXANDER LUND, OF LONDON, ENGLAND, ASSIGNOR TO THE STANDARD TIME COMPANY, OF NEW HAVEN, CONNECTICUT.

APPARATUS FOR SYNCHRONIZING CLOCKS.

SPECIFICATION forming part of Letters Patent No. 312,482, dated February 17, 1885.

Application filed May 21, 1884. (No model.) Patented in England January 1, 1884, No. 241, and in France February 25, 1884, No. 160,543.

To all whom it may concern:

Be it known that I, JOHN ALEXANDER LUND, of London, England, have invented a new Improvement in Apparatus for Synchronizing 5 Clocks; and I do hereby declare the following, when taken in connection with accompanying drawings and the letters of reference marked thereon, to be a full, clear, and exact description of the same, and which said drawings constitute part of this specification, and represent, in—

Figure 1, a front view of a portion of a clock-dial, showing the synchronizing-fingers; Fig. 2, a top view of the synchronizing mechanism; Fig. 3, a transverse section on line $x-x$ of Fig. 2, looking forward, and showing the arms in their normal or inactive condition; Fig. 4, a sectional side view showing the parts in their normal condition or open circuit; Fig. 5, the same, showing the circuit closed; Fig. 6, the same as Fig. 3, showing the arms as in the closed or synchronizing position; Fig. 7, a front view of the synchronizing-fingers, to illustrate the operation of the 25 pointer thereon when the left-hand finger is from any cause caught in its down position.

This invention relates to an improvement in apparatus for synchronizing clocks, such as employ a pair of fingers working through a 30 slot in the dial of the clock, and which, as the minute-pointer approaches twelve, or the termination of the hour, will be brought together one upon one side and the other upon the opposite side, so as to turn the pointer to 35 the true time, if it be fast or slow, and such as known as the "Lund synchronizer."

In the more general construction of this class of synchronizers the movement of the fingers is from their extreme open position to the central position, one upon one side and the other upon the opposite side of the pointer. This movement having been accomplished, the fingers are designed to return to their extreme position to permit the pointer to proceed.

45 It not infrequently occurs that, through some derangement of the circuit or mechanism, the pointers are brought together out of time and will remain in their closed or setting position. In such case, as the pointer 50 advances to twelve, or the close of the hour, it

will strike the left-hand finger, and its further movement will be arrested, so that not only is the clock stopped, but the synchronizing-fingers are locked, so as to prevent their return, and the clock cannot be started until 55 the parts are readjusted.

The object of my invention is to overcome this difficulty; and it consists in hanging one (the left-hand) or both the fingers upon a pivot upon which the fingers, one (the left-hand) or 60 both, may swing from one extreme to the other, whereby should the fingers be brought together before the proper time, and the pointer then strike the left-hand finger, it will easily 65 pass on, carrying the finger toward the other extreme until the pointer will escape, the said finger counterbalanced, so that after the pointer has thus escaped it will automatically be returned, and thus will not interfere with the proper running of the clock should the synchronizing mechanism be out of order, and as 70 more fully hereinafter described.

As represented in Fig. 3, two arms, a b , are hung upon a pivot, d , and so as to swing in a plane parallel with the clock-dial, as shown. 75 These arms are in rear of the clock-dial. Through the dial is a segment-shaped slot, e , of which the pivot d is the center.

From the arm a a finger, f , projects through the slot, as seen in Figs. 1 and 2, and from the other arm, b , a like finger, g , projects through the slot, substantially as do the fingers in the Lund synchronizer. The normal positions of these fingers are at their respective ends of the slot, and at such a distance from the path 80 of the minute-pointer h that that pointer may pass both pins, as seen in Fig. 1. The arms a b are counterbalanced, the one, a , by a weight, i , the other, b , by a weight, k , these counterbalancing-weights being upon the opposite 85 side of the pivot, and so that these weights by their own gravity serve to hold the arms at their respective extremes, and as seen in Fig. 3. From the hub of the arm a is a projection, l , on the same side of the hub as the arm, and from the arm b is a like projection, m .

n is an armature of a magnet, A , to which the lines run in the usual manner, and so that when the circuit is closed the armature will be attracted to the magnet. From the arma- 100

ture two fingers, *o p*, project forward, the one, *o*, standing over the projection *l* on the arm *a*, the other, *p*, over the projection *m* of the arm *b*. When the circuit is broken and the armature away from the magnet, as seen in Fig. 4, the fingers *o p* are raised from the projections *m l*, so as to permit the fingers *f g* to stand at their respective extremes; but when the circuit is closed to draw the armature to the magnet, as seen in Fig. 5, then the fingers *o p* are thrown down upon the projections *l m* and turn the arms *a b*, bringing the fingers together, as seen in Fig. 6, which is the synchronizing position. So soon as the circuit is broken the armature leaves the magnet. Then the fingers *f g* are free, and return by their counterbalance to their two extreme or normal positions, as seen in Fig. 3. If through any defect in the circuit or mechanism the left-hand finger *f*, should come to its central position, as seen in Fig. 7, out of time and there remain, or come down in advance of the pointer *h*, then the pointer will strike that finger, as seen in Fig. 7, and because the finger is free from the mechanism which operates the synchronizer the pointer will carry the finger onward until it can escape therefrom, as also indicated in Fig. 7. Then the finger is free to return under the influence of the counter-balance.

30 I claim—

1. A mechanism for synchronizing clocks, substantially such as described, consisting of a pair of fingers arranged to approach each other to turn the pointer at a predetermined time, one of said fingers projecting from an arm hung upon a pivot to swing in a plane substantially parallel with the plane of the dial, and provided with a counter balance ar-

ranged to permit the said one finger to be turned toward the opposite extreme under the action of the pointer, and so that as it approaches the opposite extreme the pointer will escape therefrom, the said counter-balance serving to return said finger, and mechanism, substantially such as described, for turning said fingers at a predetermined time, substantially as specified.

2. In a clock-synchronizing mechanism, the combination of the two arms *a b*, hung upon a pivot to swing in a plane parallel with the plane of the dial, said arms carrying, respectively, synchronizing-fingers *f g*, and also provided with counterbalancing-weights, respectively, *i k*, and mechanism, substantially such as described, for turning said arms and fingers at predetermined times to operate upon the pointers of the clock, said counter-balance serving to return said fingers, substantially as specified.

3. In a synchronizing mechanism for clocks, the combination of the two arms *a b*, carrying, respectively, synchronizing-fingers *f g*, and each provided with counterbalancing-weights, respectively, *i k*, a magnet and its armature, the armature provided with fingers *o p*, arranged to bear upon said arms to operate the synchronizing-fingers when the circuit is closed and release said arms when the circuit is broken, substantially as described.

JOHN ALEXANDER LUND.
